UNITED STATES PATENT OFFICE

129,177

DESIGN FOR A TOOL GRINDING MACHINE

Robert B. Pealer, Garrettsville, Ohio, assignor to
Beaver Pipe Tools, Inc., Warren, Ohio, a cor-
poration of Ohio

Application April 14, 1941, Serial No. 100,364

Term of patent 14 years

To whom it may concern:

Be it known that I, Robert B. Pealer, a citizen of the United States of America, residing at Garrettsville, in the county of Portage and State of Ohio, have invented a new, original, and ornamental Design for a Tool Grinding Machine, of which the following is a specification, reference being had to the accompanying drawings, forming part thereof.

Fig. 1 is a view in perspective of the front and left end of a tool grinding machine showing my new design;

Fig. 2 is a view in elevation of the right hand end thereof; and

Fig. 3 is a rear elevational view thereof.

The design for the tool grinding machine illustrated is characterized by the grinding wheel and the tool holder appearing on the right of the article in Fig. 1, on the end in Fig. 2, and on the left in Fig. 3, having the specific configuration shown.

I claim:

The ornamental design for a tool grinding machine, substantially as shown and described.

ROBERT B. PEALER.
